UNITED STATES PATENT OFFICE.

FRED R. BELT, OF CHICAGO, ILLINOIS, ASSIGNOR TO FRED R. BELT COMPANY, OF CHICAGO, ILLINOIS, A CORPORATION OF ILLINOIS.

DESIGN FOR A MINER'S LAMP.

Application filed April 19, 1923. Serial No. 5,853. Term of patent 14 years.

To all whom it may concern:

Be it known that I, FRED R. BELT, a citizen of the United States, residing at Chicago, in the county of Cook and State of Illinois, have invented a new, original, and ornamental Design for a Miner's Lamp, of which the following is a specification, reference being had to the accompanying drawing, forming a part thereof, in which—

Fig. 1 is a plan elevation and

Fig. 2 is a side elevation showing my new design.

I claim:

The ornamental design for a miner's lamp as shown.

FRED R. BELT.
